UNITED STATES PATENT OFFICE

LESTER S. KAUFFMAN, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A FLUE-GAS DEFLECTOR FOR RANGES

Application filed April 3, 1930. Serial No. 35,146. Term of patent 14 years.

To all whom it may concern:

Be it known that I, LESTER S. KAUFFMAN, a citizen of the United States, residing in the city of St. Louis and State of Missouri, have invented a new, original, and ornamental Design for a Flue-Gas Deflector for Ranges, of which the following is a specification, reference being had therein to the accompanying drawings, forming a part thereof.

In the drawings:

Figure 1 is a front elevation of the article, showing my new design.

Figure 2 is a side elevation thereof.

I claim:

The ornamental design for a flue gas deflector for ranges, as shown.

In testimony whereof, I hereunto affix my signature.

LESTER S. KAUFFMAN.
